(57) **CLAIM**

The ornamental design for a device for training and instruction, as shown.

DESCRIPTION

This invention was made with government support under Contract No. W15QKN1930003 awarded by the U.S. Army Contracting Command. The government has certain rights in the invention.

FIG. 1 is a front perspective view of the device for training and instruction showing our new design.

FIG. 2 is a front elevational view thereof;

FIG. 3 is a back elevational view thereof;

FIG. 4 is a side elevational view thereof;

FIG. 5 is another side elevational view thereof;

FIG. 6 is a top plan view thereof; and,

FIG. 7 is a bottom plan view thereof.

The broken lines showing portions of the design in all figures are included for the purpose of illustrating environment and do not form part of the claimed design.
